UNITED STATES PATENT OFFICE.

LEWIS J. HART AND FRANKLIN R. WHITE, OF WATERBURY, CONNECTICUT,
ASSIGNORS TO THE PATENT BUTTON COMPANY, OF WATERBURY, CONNECTICUT, A CORPORATION OF CONNECTICUT.

BUTTON.

1,378,108.

Specification of Letters Patent. Patented May 17, 1921.

Application filed February 16, 1920. Serial No. 358,881.

To all whom it may concern:

Be it known that we, LEWIS J. HART, a citizen of the United States, and a resident of Waterbury, in the county of New Haven and State of Connecticut, and FRANKLIN R. WHITE, a citizen of the United States, and a resident of Waterbury, in the county of New Haven and State of Connecticut, have made and invented certain new and useful

10 Improvements in Buttons, of which the following is a specification.

Our invention relates to buttons, and particularly to that class or type in which the fastener is inserted or driven through the material to which the button is to be secured, through the imperforate base of the button proper and then headed or turned upon itself so as to securely lock and fasten the button in place.

20 It has heretofore been the practice to form buttons of this class entirely of metal. There are some decided disadvantages, however, to an all-metal button, among which may be mentioned the tendency for the button to change appearance as soon as the finish upon the surface of the button starts to wear. Further the wearing of the surface of the button may expose the base metal of which the button is formed and 25 allow the latter to rust and corrode and in turn discolor and mar the cloth to which the button is attached. Further the increasing cost attending the manufacture of buttons of metal has made it desirable that 30 an efficient substitute be found.

35 It is accordingly an object of our invention to provide a button having a non-metallic body portion, which is substantially chemically inert so as to resist the corroding 40 influence of moisture and so constructed that the body portion is of uniform color throughout, whereby the button will present a neat and pleasing appearance, although the surface thereof become worn or scarred.

45 A further object is to provide a button composed of metallic and non-metallic portions, so combined and arranged as to prevent undue wear upon the non-metallic portions and so formed as to be capable of being fastened to cloth or other material by 50 an automatic button attaching machine, and without danger of the non-metallic portions of the button splitting or cracking.

A further object is to provide a button

composed of a non-metallic fibrous body, 55 which may be pressed, molded, or otherwise shaped and more economically produced than a corresponding button formed entirely of metal.

With the foregoing and other objects in view, our invention resides in the novel button herein described and illustrated and in certain modifications thereof and in the combination and arrangement of parts and in the details of construction thereof as will 60 65 more fully hereinafter appear.

In the accompanying drawings, the preferred embodiment of our invention is shown, wherein: —

Figure 1 is a view in vertical section of a 70 button embodying the characteristic features of our invention.

Fig. 2 is a similar view, showing the button attached and securely anchored to cloth or other material.

Fig. 3 is a top plan view of the foregoing.

Fig. 4 is a view in vertical section of our improved button, the fastener being formed with a single prong.

Fig. 5 is a similar view, showing this button securely anchored to the cloth.

Fig. 6 is a view in vertical section of a somewhat modified form of button, a metallic reinforcing plate being included in 85 the base of the button, so as to prevent the undue wear of the latter.

Fig. 7 is a perspective view of the metallic reinforcing plate shown in Fig. 6.

Referring specifically to the several views, 90 wherein similar reference numerals designate corresponding parts throughout, the fastener A, is formed with the upstanding prongs 10, which are adapted to pierce the cloth or material B, to which the button is to be attached. The body of the button C is formed with the head or flange 11, having the downwardly projecting hub 12, and the imperforate base 13. The imperforate base is provided with the indentations or grooves 14, which are adapted to receive the prongs of the fastener and properly guide and direct them through the base.

100 105 In order that the body of the button C will be of uniform color throughout, and substantially chemically inert, so as to resist the corroding effect of the moisture of the

atmosphere, we prefer to form it of a hard non-metallic fibrous material, which by suitable treatment may be rendered sufficiently ductile and plastic, so that it may be pressed, 5 molded or in other ways formed to shape, allowing the body of the button to be economically produced in large quantities and at less cost than when formed of metal, which has heretofore been exclusively used 10 in the manufacture of the present class of buttons.

The non-metallic and fibrous material of which the button is formed allows it to be made of any desired color and of uniform 15 color throughout, so that it will present a neat and pleasing appearance although the surface of the button be worn and marred. Further the non-metallic material being substantially chemically inert, will not dis- 20 color or damage the material to which it is secured, even though it be subjected to the most adverse conditions, such as when exposed to the salt air of the sea coast.

In those instances where the material 25 through which the fastener extends, or the conditions under which the button is to be used, would allow the slight relative movement of the body and fastener, we prefer to insert within the hub of the button a 30 metallic reinforcement 15, having an opening 16, extending therethrough for the re- ception of the holding prong of the fastener. During the securement of the button to the 35 cloth by an automatic button attaching ma- chine, the die, of the machine, (not shown) strikes against the point of the fastener and heads it down upon the metallic reinforce-

ment as illustrated in Fig. 6. The base of the button is accordingly protected against wear by the head of the fastener and thus 40 provides for the long and useful life of the button.

Having thus described our invention, what we claim is:—

1. A button comprising a body portion in- 45 cluding a head, a hub and an imperforate base formed of a hard, non-metallic mate- rial, said base provided with an indentation adapted to receive and guide the prong of a metallic fastener through the base for se- 50 curement of the button to a supporting surface.

2. A button comprising a body portion formed of a hard, non-metallic material and provided with an imperforate base, a metallic reinforcement bearing against the upper surface of the base and provided with an aperture therethrough, said base provided with an indentation in alignment with the aperture of the metallic reinforcement and adapted to receive and guide the prong of a metallic fastener through said base and through the aperture of the metallic reinforcement for securement of the button to a supporting surface. 55

Signed at Waterbury, in the county of New Haven, and State of Connecticut, this 11th day of Feb., A. D. 1920.

L. J. HART.
FRANKLIN R. WHITE.
